UNITED STATES PATENT OFFICE.

CURTIS HUSSEY VEEDER, OF HARTFORD, CONNECTICUT.

DRAPERY HANGER.

Application filed March 7, 1928. Serial No. 259,720.

This invention relates particularly to such supports or hangers for curtains or draperies which are sometimes used in conjunction with casement windows. Draperies are sometimes supported by rings on fixed rods above the tops of casement windows and care must be taken to push them back well out of the way before the window is opened. It has also been proposed to hang such draperies on rigid cranes which can be swung on vertical axes so as to permit free opening of the window, but such cranes are unsightly when swung into the room. In hangers of both kinds the movement of the draperies is sometimes effected by cords and pulleys, with the result that the drapery is apt to be bunched at one side and is not uniformly distributed especially when it is desired to move the drapery to an intermediate position. The object of the invention is to provide a hanger which shall be free from the objections to the types of hanger heretofore employed and shall be capable of being manipulated readily and without the use of cords and pulleys and fastening devices. The improved hanger embodies the principle of the lazy tongs, but in such form as to provide for the support of the drapery, its uniform distribution in all positions and the maintenance of the supporting points in a substantially straight and horizontal line in all positions. Provision may also be made for the support of a fixed, heavy drapery, such as is sometimes used at the side of a window in conjunction with the lighter drapery which is to be moved across the window. The invention will be more fully explained hereinafter with reference to the accompanying drawing in which it is illustrated and in which:

Figure 1 is a view of the improved hanger as seen from above partly in horizontal section on the plane indicated by the broken line 1—1 of Figure 2. Figure 2 is a view of the hanger in elevation, with some parts in section, the drapery support being shown by full lines in extended position and by broken lines in its retracted position. Figure 3 is a view of the hanger as seen from above and extended with the addition

of a support for a heavy drapery at the side of the window.

Figure 4 is a view in elevation of the parts shown in Figure 3.

Figure 5 is a detail view of the bottom supporting bracket.

Figure 6 is a detail view in section on the plane indicated by the broken line 6—6 of Figure 5.

Figure 7 is a detail view of the parts shown in Figures 5 and 6, partly in elevation and partly in section on a plane of section different from that of Figure 6.

To the casing of the window, at each side, are secured an upper bracket *a* and a lower bracket *b*. The two upper brackets *a*, at opposite sides of the window, may be arranged to support, above the top of the window, the usual shade roller *a*.

In the brackets *a* and *b* is mounted a rod *c* so that it may turn on a vertical axis. Preferably the rod *c* is hollow as indicated in Figures 5, 6 and 7. At the lower end of the rod *c* is arranged a detent to retain the hanger in either of its two positions, that is, parallel with the plane of the window or swung into the room. This detent may be of any suitable construction. As shown the lower end of the rod is provided with a bushing *c*¹, flanged as at *c*². The bushing receives a pin *b*¹ which may be threaded into the arm *b*, and in the underside of the flange *c*² are formed recesses *c*³, *c*⁴ for cooperation with a beveled pin *b*², to position the rod *c* in its turning movement. At its upper end the rod *c* carries a pin *c*⁵ in engagement with the bracket *a*.

At its upper end the rod *c* is provided with a collar *c*⁶ for a purpose to be described, and slidably mounted on the rod *c* is a sleeve *d*. The rod *c* and the sleeve *d* are incapable of relative rotatory movement, and for this purpose the rod and the sleeve are shown as polygonal. At its lower end the sleeve *d* is provided with a handle *d*¹, by which the sleeve *d* may be raised or lowered and the rod *c* may be caused to have a partial rotation. Also mounted on the handle *d*¹ is a spring pressed clamp *d*² having a member *d*³ which is arranged to bear against the rod *c* through an opening formed at *d*⁴ in the sleeve

d. The function of this clamping device is to retain the sleeve at the desired vertical position on the rod c. The sleeve d is provided, at a suitable distance below its upper end, with a collar d⁶.

The lazy tongs, by which the drapery is directly supported, is operated through the change in relative position of the collars c⁶ and d⁶. When the collar d⁶ is in its highest position, as shown in Figures 2 and 4, the lazy tongs is fully extended, that portion of the sleeve above the collar d⁶ acting as a stop to limit the extension of the lazy tongs. The lazy tongs must be so formed that the points of support of the drapery shall be in a substantially straight line and in substantially the same horizontal plane in all positions of the lazy tongs. To this end the main member e of the lazy tongs is pivotally mounted upon the movable collar d⁶ and from that point extends upward and outward. The second member e¹ is pivotally mounted at one end on the collar c⁶ and at the other end, as at e², is pivotally connected to the middle point of the member e, its length being substantially one-half of the length of the member e. Two members e³ forming a pair and each having a length substantially one-half of the length of the member e¹ are pivotally connected, as at the point e⁴, to the middle point of the member e¹, and as at the point e⁵, to the middle of the outer half of the member e, and are pivotally connected together as at the point e⁶. In like manner pairs of members e⁷ and members e⁸ are pivotally connected to the middle points of the coating members or half members e³, e¹, and e, and are pivotally connected together as at the points e⁹. At the pivot on the collar c⁶, at the point e⁶, at each of the points e⁹, and at the outer extremity of the member e is located a device e¹⁰ for engagement with the drapery, such device being represented in this instance as a button adapted to engage a button hole formed in the drapery. The points of location of the button holes e¹⁰ form apices of the lazy tongs and by reason of the provision of the continuous member e of the lazy tongs and the proportioning and pivoting of the intermediate members these apices or points of attachment of the drapery remain substantial-

ly in the same horizontal plane in all positions of the lazy tongs as illustrated in Figures 1 and 4, so that the upper edge of the drapery is always in the same horizontal plane, at least as to the points of attachment. It will be noted that the subordinate members, such as e³, e⁷, etc., are proportioned and pivotally connected so as to form parallelograms.

It will be understood that by manipulation of the handle d¹ the lazy tongs may be extended more or less, as desired, carrying the drapery with it, and that, whether the lazy tongs be extended or retracted, the lazy tongs and the drapery may be placed either parallel with the plane of the window or swung into the room to afford free opening.

If it is desired to have a heavy drapery at the side of the window in addition to the lighter drapery carried by the lazy tongs, an arm f may be secured to the rod c or the collar e⁶ to support such heavy drapery and to be capable of being swung into the room when necessary to afford a free opening. In other respects the construction shown in Figures 3 and 4 is identical with that shown in Figures 1 and 2 and no further description is necessary.

It will be understood that various details in construction and arrangement can be made to suit different conditions of use and that except as pointed out in the accompanying claims the invention is not restricted to the precise construction shown and described herein.

I claim as my invention:

A drapery hanger comprising a rod capable of partial rotation about its axis, a sleeve movable longitudinally on the rod, a handle connected to the sleeve to effect partial rotation of the sleeve and rod and relative longitudinal movement of the sleeve and rod, a clamp to retain the sleeve and rod in relative position, a lazy tongs having one of its members connected to the rod and another of its members connected to the sleeve, and supporting devices carried by the lazy tongs for engagement with the drapery.

This specification signed this 3rd day of March, A. D. 1928.

CURTIS HUSSEY VEEDER.
